UNITED STATES PATENT OFFICE.

FERDINAND J. KALLENBACH, OF BROOKLYN, NEW YORK.

PROCESS OF PRINTING ON TWO-COLOR LITHOGRAPHIC PRESSES.

SPECIFICATION forming part of Letters Patent No. 595,716, dated December 21, 1897.

Application filed August 7, 1897. Serial No. 647,481. (No specimens.)

To all whom it may concern:

Be it known that I, FERDINAND J. KALLENBACH, a citizen of the United States, residing at Brooklyn, Kings county, New York, have 5 invented certain new and useful Improvements in the Art of Printing on Two-Color Lithographic Presses, of which the following is a specification.

This invention has relation to printing in 10 colors from surfaces—as those of lithographic stones, for example—where the printing is to be done on two-color presses.

The difficulty heretofore experienced in 15 printing two colors in succession on a two-color lithographic press has been that the wet color applied to the sheet from the first stone sets off on the second stone from the sheet while it is receiving the second color, and after a few impressions the second stone begins 20 to take the second color at this point, which is then printed on the sheet in the form of a smutch and directly on the spot where the first color has been printed by the first stone. This difficulty does not occur in printing on 25 single-color presses, as the color previously printed on the sheet is allowed to dry before the next color is printed; but in two-color presses the second color is printed before the first becomes dry.

30 I have discovered that by first selecting and classifying certain colors and tints to be used in printing a work in color, then grouping these colors and tints in couples in a certain order, and then placing the colors or tints of 35 each couple on the stones of the two-color press in a certain order such a press may be employed successfully in producing multi-colored work. For example, if the two colors or tints to be printed on the two-color press 40 be of such a character that they may be superimposed while wet, the stronger and darker color or tint being printed from the first stone or plate and the weaker and lighter from the second stone or plate, and the two tints or 45 colors selected for the printing be of such a character that the lighter may be printed on or over the darker without injury to the latter, then excellent work may be done with a two-color press; and it is the art of thus selecting the colors or tints, arranging them in 50 pairs or couples, and preparing the stones or plates with the colors or tints of the pair in

the proper order or sequence that constitutes the essential features of my invention.

It is also desirable in the selection and arrangement of the colors or tints in the picture to be printed in colors that the darker of the two colors of the pair shall cover surfaces of less or no greater area than the lighter color of the pair and that the spots or figures of the 55 darker color shall be included in the area covered by the lighter color, and this is generally the arrangement in a colored picture.

In carrying out my invention I classify the colors or tints to be used in pairs, for harmony, and on the basis that the lighter of the two colors may be superimposed on the darker while the latter is wet without injury to the darker color. Also, in arranging the colors in the picture I aim to include the areas 60 to be covered by the darker color within the area or areas to be covered by the lighter color. Then in preparing the stones or plates the darker color is transferred to the first stone or plate in the two-color press and the 65 lighter color is transferred to the second stone in the press.

In the accompanying drawings, which illustrate my invention, Figure 1 shows the first stone with the darker color transferred 70 thereto, and Fig. 2 shows the second stone with the lighter color transferred thereto. Fig. 3 shows the sheet with both colors of the 75 design or picture printed thereon successively by the two stones.

To illustrate the operation, suppose, for example, the pair of colors or tints selected are dark blue and light blue, the dark blue *a* to be printed from the first stone *A* in Fig. 1 and the light blue *b* to be printed from the 80 second stone *B* in Fig. 2. In the process of printing from these stones the darker color *a* is first printed on the sheet *C*, (seen in Fig. 85 3,) and the sheet then passes, while the darker ink is yet wet, to the second stone *B* to receive 90 the lighter color *b*; but the great pressure of the sheet *C* on the second stone will, owing to the fatty nature of the ink, cause the fat from this ink to overcome the resistance offered by the water on the second stone and 95 thus prepare this latter stone to take ink at the points where the dark-blue ink has been brought into contact with it. This effect is 100 not apt to be produced until after a few im-

pressions have been made, as the water on the second stone will offer some resistance; but after a time the light-blue ink from the roller which supplies ink to the second stone 5 will be applied on the spots referred to, and this ink will be printed over or on the dark-blue ink on the sheet. The effect of this will be rather to intensify or increase the depth of the dark-blue color, if it be noticeable at 10 all, and the operator will in preparing his tints make due allowance for this. There will be no difference of color produced in this case, but only a slight difference of intensity of the darker color, due to the application of 15 one on the other while wet. Fig. 3 shows the sheet C with the two colors *a* and *b* printed thereon from the stones A and B. If the lighter color were transferred to the first stone A and the darker color to the second 20 stone B, the effect would be that the lighter color, under the pressure in the press, would prepare the second stone to receive the darker ink at the points where the lighter ink on the sheet was impressed upon it, and these points 25 would take up the darker ink from the roller. Consequently after a few impressions the darker ink would be printed on the sheet over the whole design, the darker ink being printed over that portion of the design printed in the 30 lighter ink from the first stone and practically obscuring it. Hence the darker color must be printed from the first stone. As stated above, the effect of printing with the lighter color over the darker, both colors being in an 35 undried or wet condition on the sheet and selected according to my invention, is to intensify the darker color slightly, but not to produce a different color. Where a different color is to be produced by superimposing colors, it is preferable to print the second color 40 after the first is dry. For example, such colors as green, produced by superimposing blue on yellow, or purple, produced by superimposing blue on red, may be produced on a 45 two-color press; but, as stated above, it is best to allow the first color to dry before the second is applied. For this reason the formation of greens, purples, and the like on a two-color press will usually follow that of ordinary single-color presswork—that is, the 50 two colors required to produce the compound color will not be put on the press and printed at the same time.

In choosing colors in pairs that will harmonize and mix or blend properly when superimposed or run together the ordinary pigment colors, red, pink, dark blue, light blue, 55 deep yellow, pale yellow, black, and gray,

may be paired as follows: red first, pink second; dark blue first, light blue second; 60 deep yellow first, pale yellow second; black first, gray second. With inks of these colors arranged in this way, run through a two-color press four times, an eight-color picture or 65 lithograph may be produced without difficulty, provided the directions given above for the arrangement of the colors is followed.

My method of printing on a two-color press is applicable to what is generally designated "lithographic" printing, whether it be done 70 from a stone, an aluminium plate, or other plate absorbent of water.

It must be understood that while I have referred to the printing of an eight-color picture and have given examples of eight pairs 75 of colors I do not limit myself to any numbers of colors in the picture, nor to any particular pair of colors or tints. These will of course be subject to conditions. There might be in some pictures only two colors required and in others ten or more colors, and other colors or tints than those named may be arranged in pairs. 80

Having thus described my invention, I claim— 85

1. The herein-described improvement in the art of printing on two-color, lithographic presses, which consists in first selecting two colors or tints, one darker or stronger than the other, which may be superimposed in printing while wet, without injury to the darker color, and then transferring the darker color 90 to the first stone or plate of the press and the lighter to the second stone or plate thereof, substantially as set forth. 95

2. The herein-described improvement in the art of printing on two-color, lithographic presses, which consists in first selecting the colors or tints to be used and arranging them in pairs for application to the picture to be 100 printed, each pair consisting of two colors or tints, one darker than the other, which may be superimposed in printing without injury to the darker color, and then transferring the darker colors to the first stones or plates to 105 be used on the two-color press and the lighter colors to the second stones or plates to be used, substantially as set forth.

In witness whereof I have hereunto signed my name in the presence of two subscribing 110 witnesses.

FERDINAND J. KALLENBACII.
